WILLIAM HANLEY, OF EAST ORANGE, NEW JERSEY, ASSIGNOR TO FERGUSON BROTHERS MANUFACTURING COMPANY, OF HOBOKEN, NEW JERSEY, A CORPORATION OF NEW JERSEY

LAP TABLE

Application filed April 12, 1929. Serial No. 354,535.

The object of my invention is to provide a lap table which will be particularly well adapted for use as a solitaire card table, or as a writing, sewing or reading table.

My invention generally comprises a lap table which is partly supported by a rotatively and vertically adjustable reversible leg and partly supported by the lap of the user, or by the arms of a chair occupied by the user, the leg being adapted to be swung from its inoperative position in the plane of the table top along the outer edge thereof, to its operative position at substantially right angles to the table top in either of two directions and also being adapted to be adjusted to bring the table top to the desired height or inclination; means being provided for locking the leg in its different positions.

My invention more particularly comprises a reversible lap table in which the table top is provided with two usable surfaces and in which the leg may be swung in either direction from its inoperative position to its operative position, so that either one of the opposite surfaces of the table top may be used, thus materially lengthening the useful life of the table.

A practical embodiment of my invention is represented in the accompanying drawings, in which:

Fig. 1 represents a plan view of the lap table showing the leg in its folded or inoperative position, located in the plane of the table top along the outer edge thereof;

Fig. 2 represents an end view of the table; Fig. 3 represents a front view of the table;

Fig. 4 represents a plan view of the table with the leg in its unfolded or operative position at substantially right angles to the table top;

Fig. 5 represents an end view of the table; Fig. 6 represents a front view of the table;

Fig. 7 represents a detail section on an enlarged scale, taken in the plane of the line VII—VII of Fig. 1, looking in the direction of the arrows; and

Fig. 8 represents a detail section on an enlarged scale, taken in the plane of the line VIII—VIII of Fig. 5, looking in the direction of the arrows.

The lap table comprises a table top and a rotatively and vertically adjustable reversible leg connected to the outer edge thereof. The table top has both of its sides provided with flat unbroken usable surfaces so that it may be used either side up, according to the operative position of the leg. The table top comprises a suitable boundary frame 1 having, in the present instance, oppositely disposed rabbets 2 and 3 along its inner peripheral edges, within which rabbets the peripheral edges of two spaced apart sheets 4 and 5 of cardboard or other stiff material are seated and secured substantially flush with the opposite faces of the frame. These sheets 4 and 5 are preferably provided with flexible covers 6 and 7 of suitable material, as, for instance, artificial leather, silk or the like, may be provided for the sheets 4 and 5, the peripheral edges of which flexible covers are tucked and secured within oppositely disposed kerfs 8 and 9 extending along the opposite faces of the boundary frame 1 and spaced outwardly from their respective rabbets 2 and 3.

The boundary frame 1 along the outer front edge of the table top also has a leg receiving cross recess 10 cut or otherwise formed therein. From the bottom of this recess a screw 11 projects outwardly, which screw, in the present instance, is secured to the frame by providing its inner end with a wood screw portion 12 engaging the frame; the outer end of the screw being provided with a machine screw portion 13 for engagement by a leg clamping nut 14.

The table leg 15 has a lengthwise elongated slot 16 through which the screw 11 projects to form a rotatable and vertically adjustable reversible support for the leg. A wearing plate or washer 17 may be located on the screw between the leg and clamping nut.

In operation:—Presuming the reversible leg to be locked in its inoperative position in the plane of the table top along its outer front edge and it be desired to bring the leg to its operative position for partly supporting the table: the clamping nut is loosened sufficiently to release the leg. The leg is then swung in either direction according to which one of

the table top surfaces is to be used, to a position substantially at right angles to the plane of the table top. When the leg reaches this position it will seat itself within the cross recess 10 in the outer front edge of the table top frame. The clamping nut may then be tightened to lock the leg firmly to the frame. If the length of the table supporting portion of the leg has to be varied, the clamping nut is loosened sufficiently to permit the vertical adjustment of the leg without removing the leg from the cross groove. When the leg has been properly adjusted, the clamping nut is again tightened to lock the leg in such adjusted position.

From the above description it will be seen that I have provided a very simple and inexpensive lap table, the height and tilt of which may be readily adjusted to suit different requirements. It will also be seen that by providing for the seating of the leg in the cross recess of the frame I am enabled to rigidly and securely lock the leg against unintentional displacement when in its operative position. It will furthermore be seen that the same clamping means may be employed for locking the leg in its inoperative position.

Furthermore, by providing for the swinging of the leg to either of two operative positions at substantially right angles to the plane of the table top I am enabled to use either of the two surfaces of the table top and thus materially prolong the useful life of the table. It will furthermore be seen that by swinging the leg into the plane of the table top along the outer front edge thereof, the table, when the leg is folded, may be readily stacked with other tables into a compact bundle for shipment or for storage.

It is evident that various changes may be resorted to in the construction, form and arrangement of the several parts without departing from the spirit and scope of my invention; hence, I do not wish to be limited to the particular embodiment herein shown and described, but

What I claim is:—

1. A lap table comprising a table top, a leg pivoted to the front edge of the table top whereby the leg may be swung into the plane of the table top to its inoperative position along said front edge or to substantially right angles to the plane of the table top to its operative position, and a common means for locking the leg in its said inoperative and operative positions.

2. A lap table comprising a table top, a longitudinally adjustable leg pivoted to the front edge of the table top whereby the leg may be swung into the plane of the table top to its inoperative position along said front edge or to substantially right angles to the plane of the table top to its operative position, and a common means for locking the leg in

its said inoperative and operative positions.

3. A reversible lap table comprising a table top, a leg pivoted to the front edge of the table top whereby the leg may be swung into the plane of the table top to its inoperative position along said front edge or to substantially right angles to the plane of the table top to its operative position, and a common means for locking the leg in its said inoperative and operative positions.

4. A reversible lap table comprising a table top, a longitudinally adjustable leg pivoted to the front edge of the table top whereby the leg may be swung into the plane of the table top to its inoperative position along said front edge or to substantially right angles to the plane of the table top to its operative position, and a common means for locking the leg in its said inoperative and operative positions.

5. A lap table comprising a table top having a screw projecting from its outer front edge, a leg having a lengthwise elongated slot through which the screw projects whereby the leg may be adjusted rotatively and vertically with respect to the table top, and a clamping nut carried by the screw for locking the leg in its different positions.

6. A lap table comprising a table top having a cross recess in its outer front edge, a screw projecting outwardly from said recess, a leg having a lengthwise elongated slot through which the screw projects to form a rotatable and vertically adjustable support for the leg, and a clamping nut carried by the screw for locking the leg in its different positions, said leg fitting within said recess when the leg is disposed in its operative position at substantially right angles to the table top.

In testimony, that I claim the foregoing as my invention, I have signed my name this 10th day of April, 1929.

WILLIAM HANLEY.
